UNITED STATES PATENT OFFICE

JONAS NORTHRUP, OF HOPEDALE, MASSACHUSETTS, ASSIGNOR TO STANDARD LOOMS, INC., OF SPARTANBURG, SOUTH CAROLINA, A CORPORATION OF SOUTH CAROLINA

BATTERY-FEED MECHANISM FOR LOOMS

Application filed February 6, 1929. Serial No. 337,875.

The present invention relates to battery feed mechanisms for looms.

The object of the present invention is to reorganize and improve battery feed mechanisms for looms, and particularly to provide a battery feed which is simple in construction and positive in operation and by which the hopper is positively retained in its proper position against the usual shocks and vibrations incident to operation of the loom. To this end, the invention consists of the battery feed mechanism hereinafter described and particularly defined in the claims.

In the accompanying drawings illustrating the preferred form of the invention, Fig. 1 is a sectional elevation of a hopper and associated parts when the transfer mechanism is inactive; Fig. 2 is a sectional elevation of the mechanism shown in Fig. 1 at the conclusion of a transfer operation; and Fig. 3 is a sectional detail view viewed from the opposite side of the apparatus.

The illustrated embodiment of the invention comprises the hopper stand 6 mounted on the loom frame 4 and the hopper disks only one of which, namely, the butt end disk 8 is shown. The disk 8 is provided with the usual bobbin seats 10. The hopper rotates on the stud 12. Secured to the hopper is a ratchet 14 having the same number of teeth as there are bobbin seats in the disk 8.

The transferrer 16 which is shown partly broken away in Figs. 1 and 2 is provided with a hub 18 which is pivoted on the stud 20 and from which depends the lever 22 connecting in the usual way with the change mechanism. At its free end, the transferrer is provided with the hammer portion 24 adapted to engage the bobbin 26 to force it from its seat into the shuttle. Mounted on the hopper stand is the abutment 28 against which the butt of the bobbin 26 engages.

After a bobbin is transferred from the hopper, the hopper is advanced by means of a pawl 30 which cooperates with the ratchet 14. The pawl is pivoted on a stud 32 in a pawl carrier 34 which is pivoted at 36 on the hopper plate 6. The pawl carrier is provided with a tail portion 38 curved to conform to the hub 18 of the transferrer

whereby upward movement of the pawl carrier is limited. The pawl carrier, it will be seen, is mounted independently of the transferrer and initial movement of the transferrer is ineffective to advance the pawl carrier. As the transferrer approaches the limit of its transfer movement, it engages a projection 40 on the pawl carrier so that in the last portion of the movement of the transferrer, the pawl carrier is moved from the position shown in Fig. 1 to that shown in Fig. 2, through a distance sufficient to move the pawl 30 over one tooth of the ratchet. A heavy spring 42 is provided for the double purpose of restoring the pawl carrier to its original position thereby feeding the hopper to advance a new bobbin to transfer position when the transferrer is retracted and of pressing the pawl 30 into engagement with the ratchet. Accordingly, the spring presses at one end on the hopper frame at 44, then coils around the pivot 36 of the pawl carrier, and presses at its other end under the pawl 30. As shown particularly in Fig. 3 the pawl is recessed or channeled at 46 to provide a seat for the end of the spring. The pawl is also provided with a downwardly extending nose 48 against which the end of the spring bears. The spring is a heavy wire spring and it will be seen that it urges the pawl carrier upwardly with considerable force. However, because of its small purchase on the pawl, it exerts only a small force on the latter, in fact, only a sufficient force to insure pressing of the pawl into proper engagement with the ratchet until the transferrer is retracted, whereupon it swings the pawl carrier upward about its pivot pin 36 and causes the feeding movement of the pawl.

The pawl 30 is provided with a tail 50 which is adapted to engage a stop 52 on the pawl carrier arm if for any reason the transferrer is removed from the stud so that the upward movement of the pawl carrier is not limited by the engagement of the tail 38 with the transferrer hub. In normal operation, the stop 52 is not engaged by the pawl.

In normal operation when the transferrer is inactive, the hopper is maintained in its

proper position with considerable rigidity. The hopper cannot be moved in a clockwise direction because of the engagement of the bobbin with the abutment 28 and the force 5 of the heavy spring 42 prevents movement of the hopper in the reverse direction. When replenishment is called for, the transferrer starts its downward movement, thereby unseating the bobbin and forcing it into the 10 shuttle. The pawl carrier and pawl remain stationary during the greater part of the movement of the transferrer, that is, until the transferrer strikes the projection 40. The movement of the pawl carrier commences approximately when the bobbin is 15 unseated. The movement imparted to the pawl carrier by the last portion of the movement of the transferrer is sufficient to retract the pawl over one tooth of the ratchet or over 20 two teeth if no bobbin was in the hopper next to the outgoing bobbin. Inasmuch as the spring presses with only light force on the pawl, there is slight tendency for the pawl to drag the ratchet back with it, particularly as the tendency is for the hopper 25 to move in a clockwise direction because of the weight of the bobbins in the hopper, after the bobbin 26 has been removed from engagement with the abutment 28. Upon 30 return movement of the transferrer, the hopper tends to rotate in a clockwise direction under the action of the spring 42, but this movement is initially limited by the striking of the fresh bobbin against the trans- 35 ferrer. As soon as the transferrer rises clear of the bobbin, the hopper is free to advance until the new bobbin is positioned against the abutment 28.

It will be seen that the present invention 40 provides a battery feed mechanism of simple construction, in which the bobbin is held under positive control during transfer.

The invention having been thus described, what is claimed is:

45 1. A battery feed mechanism for looms having, in combination, a hopper, a trans- ferrer, a pivotal mounting for the trans- ferrer, hopper advancing and holding means including a ratchet and a single pawl con- 50 structed and arranged to hold the hopper with light restraint between the feed move- ments and to advance it with strong force for feed movements as the transferrer ap- 55 proaches the limit of its transfer movement.

55 2. A battery feed mechanism for looms having, in combination, a hopper, a trans- ferrer, a pivotal mounting for the trans- ferrer, hopper advancing means including 60 one single pawl only, and a pivotally sup- ported pawl carrier upon which the pawl is 65 in turn pivotally mounted, both being sup- ported independently of the transferrer, and carrier having a projection adapted to be engaged by the transferrer as it approaches 70 the limit of its transfer movement.

3. A battery feed mechanism for looms having, in combination, a hopper, a trans- ferrer, means for pivotally mounting the transferrer, a ratchet on the hopper, a pawl, a separate pawl carrier pivoted independent- 75 ly of the transferrer and having a projection adapted to be engaged by the transferrer when the bobbin is unseated, and means for restoring the pawl carrier toward its initial position.

4. A battery feed mechanism for looms having, in combination, a hopper, a trans- ferrer, a ratchet on the hopper, a single pawl 80 for advancing the ratchet, a pawl carrier on which the pawl is pivoted, a pivotal mounting for the pawl carrier, constructed and ar- ranged to cause engagement of the trans- ferrer and the pawl carrier to move the lat- 85 ter only after the bobbin is unseated.

5. A battery feed mechanism for looms having, in combination, a hopper, a ratchet for advancing the hopper, a trans- ferrer, a pawl carrier, a pawl pivoted on the pawl car- 90 rier and engaging the ratchet, the trans- ferrer and carrier having provision for back-feed- ing the carrier to move the pawl over the ratchet, and a spring for feeding the pawl carrier with feeding force toward its original position and for pressing the pawl toward the ratchet with light pressure to hold the pawl 95 in engagement therewith.

6. A battery feed mechanism for looms having, in combination, a hopper, a ratchet on the hopper, a trans- ferrer, a pivotal mount- 100 ing for the trans- ferrer, a pawl engaging the ratchet, a pawl carrier on which the pawl is pivoted, a pivotal mounting for the pawl car- 105 rier, a projection on the pawl carrier to be engaged by the trans- ferrer as the latter approaches the limit of its transfer move- 110 ment, the pawl having a spring engaging portion close to its pivot, and a spring en- gaging the pawl and acting to give feeding movement to the pawl carrier and to press the pawl with light force against the ratchet.

7. A battery feed mechanism for looms having, in combination, a hopper, a ratchet on the hopper, a trans- ferrer, a pivotal mount- 115 ing for the trans- ferrer, a pawl engaging the ratchet, a pawl carrier on which the pawl is pivoted, a pivotal mounting for the pawl car- 120 rier, a projection on the pawl carrier to be engaged by the trans- ferrer as the latter approaches the limit of its transfer move- 125 ment, the pawl having a spring engaging portion in proximity to its pivot, and a curved spring bearing against the stationary part of the mechanism at one end and against the pawl at the other end to give feeding movement to the pawl carrier and to lightly press the pawl against the ratchet.

In testimony whereof I have signed my name to this specification.
